UNITED STATES PATENT OFFICE.

ARTHUR H. MARSCHER, OF MEMPHIS, NEW YORK, ASSIGNOR TO THE SYRACUSE FAUCET AND VALVE COMPANY, OF SYRACUSE, NEW YORK, A CORPORATION OF NEW YORK.

VALVE.

SPECIFICATION forming part of Letters Patent No. 691,400, dated January 21, 1902.

Application filed April 8, 1901. Serial No. 54,818. (No model.)

To all whom it may concern:

Be it known that I, ARTHUR H. MARSCHER, a citizen of the United States, and a resident of Memphis, in the county of Onondaga, in the State of New York, have invented new and useful Improvements in Valves, of which the following, taken in connection with the accompanying drawings, is a full, clear, and exact description.

10 This invention resides in a valve which is particularly intended to be used in connection with a tank or other receptacle for controlling its supply or discharge, it being employed in the present instance for the former purpose, although it is adapted to be used for various other purposes.

The invention also resides in the novel construction of the mechanism for operating the same.

20 The main object of the present invention is to produce a valve which shall be simple, strong, and durable in construction, quick and reliable in its action, and at the same time shall permit the valve proper to be easily 25 removed and replaced, whereby the valve can be readily cleaned or repaired when required; and, furthermore, the object of the invention is to provide simple and reliable operating mechanism which can be easily 30 and conveniently actuated by hand when desired and can be readily attached to various devices, whereby the same shall be actuated automatically.

To these ends the invention consists in the 35 novel construction and combination of parts, as hereinafter fully described, and set forth in the claims.

In the drawings, Figure 1 is a vertical transverse section of a water-tank provided 40 with my improved valve and mechanism, which valve is employed for supplying the said tank, the same being shown attached to the bottom of the tank in full lines and to the side of the tank in dotted lines. Fig. 2 45 is an enlarged detail side elevation of the valve. Fig. 3 is also a side elevation viewed at right angles to Fig. 2. Fig. 4 is a longitudinal section on line W W in Fig. 3. Fig. 5 is a transverse section on line X X in Fig.

4. Fig. 6 is a transverse section on line Y Y 50 in Fig. 4, and Fig. 7 is a transverse section on line Z Z in Fig. 4.

Referring to the drawings, A represents a water-tank, which may be of any well-known shape or construction, as it does not in any 55 way pertain to the invention.

My improved valve comprises the casing B, which may be of any suitable shape or design. Said casing is screw-threaded internally and is formed at one end with a stem 60 or shank a, which passes through the bottom or side of the tank and is secured firmly thereto by means of a nut b, applied to the screw-threaded end portion of said stem or shank and bearing against the outside of the 65 tank, as clearly shown in Fig. 1. The said stem or shank a is formed with a longitudinal passage c, constituting the inlet communicating with the casing. On the side of the casing is formed a thimble d, formed with a 70 longitudinal passage e, which constitutes the outlet. Said thimble is preferably screw-threaded externally for the attachment of an elbow-pipe f, which is used when the valve is secured to the bottom of the tank to direct 75 the water downward. By forming the said thimble with screw-threads it serves to permit the valve to be used for various purposes. (Not necessary to be stated.)

C denotes a plug which is composed of an 80 upper or outer screw-threaded portion g and a similar screw-threaded lower or inner portion h, by which threads it is turned into the casing and is thus removable therefrom. By 85 constructing the plug in this manner an annular chamber i is formed at the central portion of the plug, which chamber communicates with the outlet e. The inner portion h of said plug is formed with an outwardly-flaring passage a', extending from the inner end 90 of the plug to the chamber i and is preferably adjacent to the outlet. The inner end of the plug is formed smooth and forms a seat b' for the valve c', which consists of a disk which is formed with its engaging face smooth, 95 so as to form a tight joint with the seat, and is provided with a port d' at one side, which is preferably of segmental shape and is adapt-

ed to register with the lower end of the aforesaid passage a' of like shape, as hereinafter more fully described.

e' denotes the stem, which passes freely

- 5 through a central longitudinal channel f' , formed in the plug C, and is detachably connected at its inner or lower end to the aforesaid valve c' . Said connection of the stem and valve is as follows: The valve is formed
- 10 with a central opening g' and with two short radial slots $i' i'$, extending from said opening in opposite directions, and in the lower face of the valve are formed two recesses $h' h'$, extending from said opening in opposite directions and at right angles to the said slots.
- 15 The stem is formed at its inner end with two lugs $j j$, projecting at right angles therefrom and in opposite directions. Thus in assembling said parts the stem is inserted through
- 20 the opening g' and its lugs $j j$ made to pass through the slots $i' i'$, and the stem is then given a quarter-turn to bring the lugs into position to register with the aforesaid recesses $h' h'$. The upper or outer end portion of the
- 25 stem e' is screw-threaded, to which is secured a bevel-pinion a^2 , which abuts against a shoulder a^3 , formed on the stem, which shoulder serves to prevent the pinion from turning down on the stem when power is applied there-
- 30 to, as hereinafter described.

The outer end of the plug C is formed with a central socket b^2 , through which the stem passes, and in said socket is a coiled spring c^2 , surrounding the stem and bearing against

- 35 the inner face of the pinion, whereby the stem is drawn outward to cause its lugs $j j$ to enter the recesses $h' h'$ in the valve. Thus said stem is locked to the valve and the said valve held firmly to its seat on the inner end of the plug.

40 The said spring bearing on the inner face of the pinion and drawing out the stem also holds the pinion out of contact with the outer end of the plug, thus preventing friction between the two parts. To the outer end of the stem

- 45 is applied a jam-nut d^2 , which bears on the outer face of the pinion, and thus serves to prevent said pinion from turning off the stem.

Upon the casing B is mounted a pair of brackets $e^2 e^3$, which are preferably of triangular shape and are secured to plates $f^2 f^3$, formed on the casing, by means of screw-bolts $g^2 g^3$. To the outer ends of said brackets is secured a stationary shaft h^2 , and on said shaft is journaled a depending oscillatory

- 55 quadrant i^2 , which is formed with a segmental gear j^2 , meshing with the aforesaid bevel-pinion a^2 . On the hub of said quadrant is formed an arm b^3 , projecting therefrom at right angles, which arm is formed with a longitudinal
- 60 screw-threaded socket c^3 and with a transverse screw-threaded socket d^3 .

D represents a float disposed within the tank A and which may be of any suitable form and is connected to the aforesaid quadrant by means of a rod e^3 , which is screw-threaded at each end. When the valve is attached to the bottom of the tank A, the said

rod e^3 engages the longitudinal socket c^3 of the arm b^3 , and when the valve is attached to the side of the tank the rod engages the transverse socket d^3 of the arm, which latter connection is illustrated by dotted lines in Fig. 1. In order to prevent the segmental gear from being crowded out of mesh with the bevel-pinion, I provide set-screws $f^3 f^3$, passing through one of the brackets e^3 and bearing on the outer side of the quadrant, as clearly shown in Figs. 2 and 3.

The valve c' is formed on its lower face, at the central portion thereof, with a housing g^3 over the attachment of the stem thereto, which housing serves to prevent escapement of the water between the stem and plug.

The operation of my described valve and its actuating mechanism is as follows, to wit: 85 When the float is in the position shown, the port of the valve proper registers with the vertical passage of the plug, which communicates with the central chamber, which in turn communicates with the outlet, (clearly shown 90 in Figs. 1 and 4,) whereby the water is allowed to pass from the inlet to the outlet into the tank. The rise of the water causes the float to ascend in the well-known manner, whereby motion is imparted to the quadrant by means 95 of the connecting-rod, and the segmental gear on said quadrant meshing with the bevel-pinion rotates the stem, thereby turning the valve to cause its port to be moved gradually out of register with the vertical passage of the plug. 100 Therefore when the float has reached a predetermined height the communication between said port and passage will have been entirely closed, and thus the supply of water cut off. It will of course be understood that 105 as the water in the tank drops and the float descends thus the various mechanisms are operated in the manner described and the valve is again opened.

I do not wish to be limited to the employment of the mechanism shown and described for operating the valve, inasmuch as other means may be used, and in instances where said mechanism is employed I do not wish to confine myself to the use of a float for controlling said mechanism, as many other devices may be combined with the same.

It will be seen that in cases where it is desired to operate the valve by hand a short rod may be substituted for the rod shown attached to the quadrant, said short rod serving as a lever, and, furthermore, if desired, the gearing may be entirely dispensed with, and in this case a hand-lever can be attached directly to the valve-stem and a nut substituted for the bevel-pinion to form a bearing for the coiled spring.

What I claim is—

1. The combination of an internally-screw-threaded casing provided with an inlet and an outlet, a screw-threaded plug secured removably in said casing and formed with a central annular chamber communicating with said outlet, and with a vertical or longitudinal pas-

sage extending from its inner end to said chamber, a disk valve seated on said inner end of the plug and provided with a port adapted to register with the said passage and communicating with the aforesaid inlet, said valve formed with a central opening and with a pair of radial slots extending from said opening in opposite directions, and formed with a pair of recesses in its inner face disposed at right angles to said slots also extending from said opening, a revoluble stem passing longitudinally through said plug and formed at its inner end with a pair of lugs extending at right angles to the stem in opposite directions therefrom, said lugs being adapted to pass through said slots and to engage the said recesses to lock said stem to the valve, a spring drawing said stem outward to hold the valve to its seat, and means to actuate said stem substantially as described.

2. The combination of an internally-screw-threaded casing formed at one end with an inlet and at one side with an outlet, a screw-threaded plug removably secured in said casing and provided with a central annular chamber communicating with the outlet and with a longitudinal passage extending from its inner end to said chamber, a valve seated on the inner end of the plug and provided with a port adapted to register with said passage and communicating with the aforesaid inlet, a revoluble stem passing longitudinally through the plug and detachably connected to the valve, a bevel-pinion secured to the outer end of the stem, a segmental gear meshing with said pinion, and suitably journaled on the casing, and means for actuating said segmental gear to oscillate said stem substantially as described.

3. The combination of an internally-screw-threaded casing formed at one end with an inlet and at one side with an outlet, a plug composed of a screw-threaded outer end portion and a screw-threaded inner end portion by which it is secured removably in said casing and formed with a central chamber communicating with the outlet, and with a longitudinal outwardly-flaring passage extending from the inner end of the plug to said chamber, a disk valve seated on the inner end of the plug and provided with a port adapted to register with said passage and communicating with the inlet, and formed with recesses, a revoluble stem passing longitudinally through the plug and formed with lugs on its inner end engaging said recesses, whereby it is detachably connected to the valve

and screw-threaded on its outer end portion, the plug formed in its outer end with a central socket through which said stem passes, a 60 bevel-pinion secured to said screw-threaded end of the stem and out of contact with the plug, a coiled spring disposed in said socket and surrounding the stem and bearing against the inner face of the pinion to hold the aforesaid lugs in engagement with the recesses and to hold the valve to its seat, and a suitably-actuated segmental gear supported on the casing and meshing with said pinion to impart oscillating motion to said stem which transmits like motion to the valve substantially as described.

4. The combination with a valve comprising a casing provided with an inlet and an outlet, a plug secured removably in said casing and formed with a central chamber communicating with said outlet and with a longitudinal passage extending from the inner end of the plug to said chamber, a valve seated on said end of the plug and provided with a 80 port adapted to register with said passage and communicating with the aforesaid inlet, and a stem passing longitudinally through the plug and detachably connected at its inner end to the valve, of a bevel-pinion secured to 85 the outer end of said stem, a pair of brackets mounted on the casing, a quadrant journaled on said brackets and provided with a segmental gear meshing with said pinion, and means actuating said quadrant substantially as de- 90 scribed.

5. The combination with a valve comprising a casing provided with an inlet and an outlet, a plug secured removably in said casing and formed with a central chamber communicating with said outlet, and with a longitudinal passage extending from the inner end of the plug to said chamber, a valve seated on said end of the plug and provided with a port adapted to register with said passage, a stem extending longitudinally through the plug and detachably connected at its inner end to the valve, of a bevel-pinion secured to the outer end of said stem, a pair of brackets mounted on the casing, a quadrant 100 journaled on said brackets and formed with a segmental gear meshing with said pinion, and a float actuating said quadrant to impart oscillatory movement to the aforesaid valve substantially as described.

ARTHUR H. MARSCHER. [L.S.]
